UNITED STATES PATENT OFFICE.

GEORGE P. PETROPOULAS, OF CHICAGO, ILLINOIS.

WATER-COOLER.

No. 858,101.

Specification of Letters Patent.

Patented June 25, 1907.

Application filed September 17, 1906. Serial No. 334,879.

To all whom it may concern:

Be it known that I, GEORGE P. PETROPOULAS, a citizen of the United States, residing at Chicago, in the county of Cook and State of Illinois, have invented a certain new and useful Improvement in Water-Coolers, (Case 1,) of which the following is a full, clear, concise, and exact description, reference being had to the accompanying drawings, forming a part 10 of this specification.

My invention relates to water coolers, its object being to provide improved construction and control therefor.

The water cooler of my invention is adapted for connection with a source of water supply, for instance with a faucet, provision being made to automatically shut off the flow of water to the cooler tank when the tank becomes filled. An ice chamber is inserted in the tank about which the water passes to be cooled. When water is withdrawn the automatic controlling means is actuated to allow the tank to be refilled, and when refilled the automatic means again shuts off the flow of water to the tank. A filter mechanism also forms part of the tank through which the water must pass before reaching the tank, being thereby filtered from all dirt and impurities. A drip or overflow pan forms the base of the cooler, being connected with the ice chest, and has an overflow which normally takes care of surplus water from the ice chamber and has also a faucet whereby it may be drained quickly.

In the accompanying drawing I have shown the arrangement and construction of the various parts of the cooler.

Figure 1 is an elevation view showing the complete cooler; Fig. 2 is a top view with the cover removed; Fig. 3 is a diametrical sectional view taken on line 3—3 of Fig. 2; and Fig. 4 is an enlarged sectional view of the filter.

The main tank 1 may be cylindrical or of any other shape and has a cover 2 which may be of any design. Extending into the tank near the top thereof is the end 3 of a filter 4 which end may be threaded into the tank wall as shown. The other end 5 of the filter 50 is threaded for connection with piping 6 or

other connecting mechanism whereby it may connect with a faucet or directly with the water pipes from which the tank is to be fed. The body of the filter is of greater diameter and composed of the two parts 7 and 8 having threaded connection at 9 with each other, as shown, these parts being reduced to form the ends 3 and 5 already mentioned. In the front end of the part 7 is a disk 9' of straining material, such as wire gauze, this disk being convex toward the entrance side of the filter and preferably held stationarily in place. Near the rear end of the part 7 is a similar disk 10 in which the openings may be of any size, preferably a little larger than those in the disk 9', this second disk being also convex toward the entrance end of the filter. This disk is preferably removable and to form a seat therefor the walls of the part 7 may be indented at several places, or may have the complete annular indentation 11 to form the annular ledge 12. Concentric with this disk 10 and secured thereto at its center is the disk or fender 13 which, however, is concave toward the entrance end of the filter. This disk is of smaller diameter than the part 7 to leave the annular space 14 between its edges and the walls of the part 7, this disk being also solid. The disk 10 may be given sufficient spring so that when slid 80 into the part 7 against the ridge 12 it will maintain itself with the disk 13 in position. The object of the fender 13 is to protect the disk 10 against the impact of the water entering through the end 5, the impact of the 85 water being taken up by the disk, and after having to a great degree lost its energy, is slowly forced over the edges of the disk and through the screen disk 10, being then forced through straining medium 15 and then 90 upwardly through the fine meshed disk 9' toward the tank; this straining medium 15 may be charcoal, sand or any other suitable substance. Impurities and foreign substances strained from the water by the disk 95 10 will drop to the bottom and into the opening 16 which connects through piping 17 with a faucet or cock 18 which may be readily secured to the side of the tank as shown. The entrance of water from the filter into the 100

tank is controlled by the cock 19 which in turn is controlled by the hollow ball 20 connected therewith by the arm 21, the adjustment being such that when the tank is full 5 the ball will be raised by the water to its uppermost position to close the valve or cock 19, and when water is taken from the tank the ball will follow the water and will open the valve 19, whereupon water will flow from 10 the filter until the tank is again filled and the valve closed when the ball again reaches its uppermost position. Water may be drawn from the tank through the faucet or other similar mechanism 22 communicating with 15 the lower end of the tank.

To suitably cool the water in the tank I provide the ice box or chamber 23 which may be square, cylindrical, or other desired shape, but which preferably extends diagonally 20 through the tank as shown, its upper end 24 being open and a door 25 being provided therefor, which door may be hinged to the tank. The section of this ice box is such 25 that the water may be freely passed thereto, also that it may contain sufficient ice to suitably cool the water. Surrounding the lower end of the water tank is a drip pan 26 which has a larger diameter than the tank and secured thereto to be concentric thereto and to leave a space between its bottom and the lower end of the tank, as shown. This pan may be secured in any manner to the tank, being here shown as secured thereto along its upper edge 27, which is curved inwardly to meet the tank. Extending from the lower end of the ice box and into the drip pan is an opening or pipe 28 whereby the surface water from the melting ice may drain into the drip pan. Extending from any 40 suitable point at the bottom of the drip pan is a faucet 29 by means of which the pan may be quickly drained. However, the water from the ice is still cool when it reaches the pan and the faucet 29 therefore is normally closed and provision made to have the cold 45 ice water fill the pan. A drip pipe 30, however, is provided which is of such diameter that the outflow therefrom will be such that sufficient water will be drained from the pan 50 to make way for the ice water from the ice box. This drip pipe 30 preferably extends from the faucet 29 from a point between the valve 31 in said faucet and the drip pan, and the upper end 32 of this drip pipe is bent over, 55 as shown, with the top just a short distance below the upper end of the drip pan, forming thus a sort of siphon arrangement, and there will be no outflow from this pipe until the drip pan has been filled and the water raised 60 in the drip pipe over the pan, whereafter the drip pipe will be drained to a level of the outlet end of the drip pipe. The faucet 22 communicating directly from the tank passes through the

wall of the drip pan and suitable bushing may be provided to prevent leakage.

65

The tank may be secured in any convenient position and may be supported on a shelf or in any other manner. The faucets 22 and 29 and the drip pipe 30 are preferably close together and an auxiliary drip pan (not shown) may be supported therein, or the entire cooler may be placed in position over a sink, which would then catch all the overflow from the faucets and drip pipe. By means of the automatic mechanism the tank is always filled immediately after withdrawal of water therefrom and the water in the tank is constantly being cooled. By means of the filter only clean water can enter the tank. As the tank is always filled, water can be withdrawn at any time from the faucet 18, but the main purpose of this faucet connection is to clean the filter and remove therefrom the sediment or foreign substances filtered from the water, the force of the water 85 entering the end 5 being sufficient to remove all sediment or foreign substances from the screen 10 and to flush out said substances and sediment through the pipe 17 and the faucet 18. The filter can be further cleaned 90 by unscrewing the cap or part 8.

75

80

85

90

95

In addition to using my invention as a water cooler, I find it convenient to supply means whereby milk, cream or other liquids may be easily and quickly cooled. For this purpose I place a secondary tank 33 within the main tank 1 and adjacent to the ice chest 23, the top of the secondary tank being open so that the liquids can be poured therein. A faucet 34 passes through the walls of the main tank and the drip pan and connects to the bottom portion of the secondary tank 33, this faucet being for the purpose of withdrawing the liquids as required.

100

I do not wish to be limited to the exact arrangement and construction here shown, as many changes may be made without departing from the spirit of my invention. The filter, for instance, might be entirely within the tank and the ice box and drip pan might also be arranged in different ways without departing from my invention.

105

I claim as new and desire to secure by Letters Patent the following claims:

110

In a water cooler, the combination with a tank for holding water to be cooled, of an ice box extending into said tank for receiving ice to cool the water therein, said ice box being disposed at an angle within said tank and secured to the vertical sides thereof, one end of said ice box being open and extending through an opening in the side of the tank, thereby facilitating the insertion of ice, a door associated therewith for closing the opening of said ice box, a cylindrical drip pan concentric with the tank and receiving the lower

115

120

125

end thereof, said drip pan being of larger diameter than the tank to form a compartment, a curved pipe for connecting the lower end of the ice box with the upper portion of the drip pan through the side of the tank whereby when the ice melts the water may flow into the drip compartment, a faucet secured to the lower portion of said drip pan, and a siphon overflow pipe extend-

ing upwardly from the faucet and adapted to periodically drain the drip pan to a certain level for each filling thereof.

In witness whereof, I hereunto subscribe my name this 11th day of Sept. A. D. 1906.
